UNITED STATES PATENT OFFICE.

FRED HENRY DAY, OF HOPEWELL, VIRGINIA.

LOCK FOR JOURNAL-BOXES.

1,241,347.

Specification of Letters Patent. Patented Sept. 25, 1917.

Application filed May 9, 1917. Serial No. 167,405.

To all whom it may concern:

Be it known that I, FRED H. DAY, a citizen of the United States, and a resident of Hopewell, in the county of Prince George 5 and State of Virginia, have invented a new and Improved Lock for Journal-Boxes, of which the following is a full, clear, and exact description.

This invention relates to journal boxes for railroad cars, and it has for its general object to provide a simple, novel and effective lock for securing the lid or door of the journal box closed. The wheels and journal bearings, being the foundation of the rolling 15 stock equipment for railroad cars, should be protected from theft of oil and packing from the boxes while the cars are in storage tracks or sidings and thereby prevent accidents while in transit, save cost of oil and 20 waste, and prevent the brasses from being destroyed by heat caused by the waste and oil being stolen, and it is to overcome these troubles that this invention is designed.

A more specific object of the invention is 25 the provision of a lock so constructed and arranged that it will be protected from being destroyed by heat developed from the journal in case the same becomes hot.

With such objects in view, and others 30 which will appear as the description proceeds, the invention comprises various novel features of construction and arrangement of parts which will be set forth with particularity in the following description and 35 claims appended hereto.

In the accompanying drawing, which 40 illustrates one embodiment of the invention and wherein similar characters of reference indicate corresponding parts in all the views,

Figure 1 is a vertical sectional view of a portion of a journal box on the line 1—1, Fig. 2;

Fig. 2 is a face view of the journal box;

Fig. 3 is a side view of the inner face of 45 the key hole plate of the lock;

Fig. 4 is a detail sectional view on the line 4—4, Fig. 1;

Figs. 5 and 6 are sectional views, respectively, on the lines 5—5 and 6—6, Fig. 2; and

Fig. 7 is a view of the key and packing bar.

Referring to the drawing, 1 designates an 55 ordinary journal box in which is housed a

journal 2, the bearing 3 and the oily waste 4 which keeps the bearing surfaces oiled.

The box is normally closed by a door or lid 5 hinged at its top to the journal box at 6.

The bottom 7 of the journal box is cast or 60 otherwise formed with a thickened wall 8 which has cored or otherwise formed therein a horizontal chamber 9 open at one side, and such open side being closed by a plate 10. This plate 10 has an aperture 11 to permit 65 the headed catch 12 on the lid 5 to enter the chamber 9. Within the chamber is a latch 13 swinging at one end on a pivot 14, the opposite end being adapted to rest on a lug 15 in a position behind the upper part of 70 the opening 11, so that when the rounded head 16 of the catch enters the opening 11, such head will strike the latch 13 and force the same upwardly until the head passes the latch, when the latter drops behind the 75 head, as shown in Figs. 1 and 5, whereby the lid will be locked in closed position. To insure positive action a spring 17 is arranged in the chamber 9 so as to press downwardly 80 on the locking latch 13. To release the latch a key 18 is inserted in the keyhole 19 of the plate 10, and by turning the key when properly positioned, the latch can be raised to permit the door or lid 5 to be opened. The key may serve as a packing bar whereby 85 the bearing box can be packed with oily waste.

From the foregoing description taken in connection with the accompanying drawing, the advantages of the construction and 90 method of operation will be readily understood by those skilled in the art to which the invention appertains, and while I have described the principle of operation, together with the device which I now consider to be 95 the best embodiment thereof, I desire to have it understood that the device shown is merely illustrative and that such changes may be made when desired as fall within the scope of the appended claims.

Having thus described my invention, I claim as new and desire to secure by Letters Patent:

1. The combination of a bearing box having in the lower portion of its front wall a 105 chamber which is out of communication with the interior of the box, said chamber having spaced apertures in its front wall, a spring pressed locking member in the said chamber, and a lid hinged to the upper por- 110

- tion of the box to swing vertically, said lid having a portion extending over one of the apertures of the chamber and provided on the inner face of said portion with a catch 5 extending into said aperture and engaging the said locking member, the uncovered aperture serving as keyhole.
2. A journal bearing box having its bottom formed with a thickened wall which is 10 provided with a chamber out of communication with the interior of the box, a plate

closing one side of the chamber and having spaced apertures, a pivoted latch in the chamber, spring means for holding the latch in locking position, a hinged lid having a 15 portion arranged to cover one of the apertures of the plate, and a catch on the lid to extend into the said aperture and interengage with the latch, the uncovered aperture serving as a key opening to receive a key to 20 release the latch.

FRED HENRY DAY.

Copies of this patent may be obtained for five cents each, by addressing the "Commissioner of Patents, Washington, D.C."
